FIG. 2 is a front view of the smart payment terminal according to the first embodiment;

FIG. 3 is a rear view of the smart payment terminal according to the first embodiment;

FIG. 4 is a left side view of the smart payment terminal according to the first embodiment;

FIG. 5 is a right side view of the smart payment terminal according to the first embodiment;

FIG. 6 is a top view of the smart payment terminal according to the first embodiment;

FIG. 7 is a bottom view of the smart payment terminal according to the first embodiment;

FIG. 8 is a first perspective view of a smart payment terminal according to a second embodiment;

FIG. 9 is a front view of the smart payment terminal according to the second embodiment;

FIG. 10 is a rear view of the smart payment terminal according to the second embodiment;

FIG. 11 is a left side view of the smart payment terminal according to the second embodiment;

FIG. 12 is a right side view of the smart payment terminal according to the second embodiment;

FIG. 13 is a top view of the smart payment terminal according to the second embodiment;

FIG. 14 is a bottom view of the smart payment terminal according to the second embodiment;

FIG. 15 is a first perspective view of a smart payment terminal according to a third embodiment;

FIG. 16 is a front view of the smart payment terminal according to the third embodiment;

FIG. 17 is a rear view of the smart payment terminal according to the third embodiment;

FIG. 18 is a left side view of the smart payment terminal according to the third embodiment;

FIG. 19 is a right side view of the smart payment terminal according to the third embodiment;

(Continued)

FIG. 20 is a top view of the smart payment terminal according to the third embodiment;
 FIG. 21 is a bottom view of the smart payment terminal according to the third embodiment;
 FIG. 22 is a second perspective view of the smart payment terminal according to the third embodiment;
 FIG. 23 is a second perspective view of the smart payment terminal according to the second embodiment; and,
